FLUORESCENT LAMP FIXTURE

Filed Sept. 11, 1940

FIG. 1

FIG. 2

HENRY DREYFUSS

INVENTOR.

BY *Lawrence Burns,*
ATTORNEY

UNITED STATES PATENT OFFICE

123,757

DESIGN FOR A FLUORESCENT LAMP FIXTURE

Henry Dreyfuss, New York, N. Y., assignor to Hy-grade Sylvania Corporation, Salem, Mass., a corporation of Massachusetts

Application September 11, 1940, Serial No. 94,945

Term of patent 14 years

To all whom it may concern:

Be it known that I, Henry Dreyfuss, citizen of the United States, residing at New York, in the county of New York and State of New York, have invented a new, original, and ornamental Design for a Fluorescent Lamp Fixture, of which the following is a specification, reference being had to the accompanying drawing, forming part thereof.

Figure 1 is a perspective view, as seen from below, of a fluorescent lamp fixture, showing my new design.

Figure 2 is an end elevational view of the same fixture.

I claim:

The ornamental design for a fluorescent lamp fixture, as shown.

HENRY DREYFUSS.
